RAILROAD SIGNALING SYSTEM

Elisée Auguste Joly, Epinay-sur-Seine, France,
assignor to Compagnie du Chemin de Fer
Métropolitain de Paris, Paris, France, a French
Société Anonyme

Application April 30, 1934, Serial No. 723,244
In France May 8, 1933

3 Claims. (Cl. 246—4)

The present invention relates to railway signaling systems and comprises novel means for the repetition on a train, of the indication given by the track signals or semaphores at the time of their passing. These signals can give four distinct indications (for example, line clear, first and second warnings and "danger" (line closed), or any other indications according to the operating requirements). The system can evidently be 5 easily adapted to a smaller number of indications, for example by the omission of the second warning; moreover, a modification enables, if necessary, a fifth indication distinct from the preceding, to be given (for example, to permit a distinction to be made between a block signal at danger and a shunting signal at danger). The signals are 10 repeated in an audible or a visible manner on the locomotive or driver's cab and they may be recorded on a tape or band at the time of their receipt.

The signaling system comprises essentially:—

(1) A local device or track apparatus, the parts of which are actuated either from the signal cabin or by the signal or semaphore in accordance with 15 the indications to be repeated.

(2) A travelling device or responsive apparatus on the locomotive or driver's vehicle, including electromagnetic relays designed to repeat or record the indications of the signals.

The electrical connection between the stationary local device and the travelling device on the locomotive or driver's cab is ensured at the moment of the passage of a train, on one hand, by the contact of metallic brushes or shoes carried by the train-vehicle with a metal contact bar, hereafter termed ramp, fixed between the running rails and preferably in the centre line of the track, from which rails it is electrically insulated, and on the other hand, by the running 30 rails and the frame of the vehicle.

The present invention is characterized by the fact that it brings into circuit, either in one direction or in the other, a source of direct current of suitable voltage (E), to which can be 35 added, in series, a source of alternating current of effective voltage half as great (viz. $E/2$), so as to produce different voltage-combinations in suitable number, allowing for example the use of any of the four following combinations:—

40 Direct voltage in one direction, with alternating voltage;

Direct voltage in the other direction, with alternating voltage;

Direct voltage in the first direction, alone;

45 Direct voltage in the other direction, alone.

Moreover, the modification mentioned above, for giving a fifth indication, utilizes the following fifth combination:—

Alternating voltage alone.

The travelling device or responsive apparatus 5 on the locomotive or driver's vehicle, is arranged so as to discriminate and to respond to the voltage-combination which has been selected among those enumerated above.

On the accompanying drawings, to which I 10 shall refer in the following description:—

Fig. 1 is a diagram of an embodiment of the invention, utilizing four voltage-combinations;

Fig. 2 shows a modified embodiment, utilizing 15 five voltage-combinations.

In both figures, the same reference letters represent the same parts.

In Fig. 1, the local device or track apparatus comprises:—

(a) A storage battery A of total voltage E (12 20 volts, for example), which can be kept on permanent charge, as shown, by an alternating current supply line 6 (at 110 volts, for example) by means of a step-down transformer T_r , a copper-oxide rectifier r_o and an adjustable resistance r_c ;

(b) A step-down transformer T_1 , the primary winding 7 of which is fed from the same supply line, and the secondary 8 of which develops an effective alternating voltage equal to $E/2$ volts (6 volts, for example);

(c) An insulated contact-bar or ramp C , fixed between the rails V at a distance L (at least a few metres) before the signal to which it relates, in such a way that at the moment of the passage of the train, the brushes AV and AR on the locomotive or vehicle come to bear on its surface thus sending current into the travelling device or responsive apparatus;

(d) A connection with the running rails V , either direct, in the case of a signaling system 40 for locomotive or direct current electric traction, or by means of the neutral point of an impedance bond r_b , in the particular case here considered of use of a block signaling system with alternating current track circuits;

(e) A two-way switch R having its arm 9 actuated by a relay 10 from the signal cabin, the arm 9 moving between contacts 11 and 12 , and serving to bring the source 8 of alternating current into circuit, in series with the source A of 50 direct current;

(f) A two-way switch B having its blades 14 and 15 also actuated by a relay 15 or mechanically from the signal cabin the blades moving between opposed contacts 21 , 22 , 23 , 24 and 25 ,

25

30

35

55

26, 27, 28, and serving to insert the source of direct voltage into the circuit in one direction or in the other;

(g) A protecting resistance r , of 3 ohms for 5 example, limiting the value of the current in case of accidental earthing of the ramp C.

The parts at the local signaling device are arranged in such a way that the arm 9 of switch R₁ may be in its "up-position" against contact 11 10 for the indications 1 and 2 of the signal (line clear and first warning, for example) and in "down-position" against contact 12 for the indications 3 and 4 (second warning and danger, for example), and that the switch B has its blades 15 in the right-hand position (closing contacts 25, 26 and 27, 28) for the indications 1 and 3 and in the left-hand position (closing contacts 21, 22 and 23, 24) for the indications 2 and 4. The potential difference between the ramp C and the 20 running rails will therefore take the following values:

(1) Oscillating between

$$+E\left(\frac{2+\sqrt{2}}{2}\right) \text{ and } +E\left(\frac{2-\sqrt{2}}{2}\right)$$

(2) Oscillating between

$$-E\left(\frac{2+\sqrt{2}}{2}\right) \text{ and } -E\left(\frac{2-\sqrt{2}}{2}\right)$$

(3) Constant and equal to $+E$

(4) Constant and equal to $-E$

according as the signal to be repeated gives the indications 1, 2, 3 or 4.

In this same Fig. 1, the travelling device on the locomotive or driver's vehicle is arranged as follows:—

The main circuit starts from the rear brush AR, making contact with the ramp C, passes 40 by the line 17 through the upper armature 18 and lower contact 20 of the upper pair of contacts 19, 20 of a relay R₀ then through the primary winding 29 of a transformer T₂, and reaches by line 30 the leading-in terminals of two relays R_b 45 and R_c having their windings mounted in parallel and connected by line 31 through the frame of the locomotive or vehicle at M to the running rails V.

The relay R_b is polarized so as to be energized 50 only by a current flowing in the positive direction from the brush AR through transformer winding 29 to the frame; the relay R_c is polarized in the opposite or negative direction. The relays R_b and R_c can be merely sensitive relays, 55 of the direct current type, placed in series with copper-oxide rectifying elements r₀ arranged or directed inversely as indicated conventionally so as to allow the current to flow in the direction corresponding to the operation desired.

To the secondary terminals of the transformer 60 T₂ is connected a relay R_a which can be energized by the output of said transformer; as represented, the secondary winding 32 is provided with a central tapping connected by line 33 to one terminal 65 of a relay R_a sensitive to direct current, the other extremity of the relay winding being connected by lines 34 and 35 to the respective ends of the transformer winding 32, so that the relay can be energized by the alternating current emitted, in certain conditions, by the secondary 70 of the transformer T₂, this current being rectified by copper-oxide rectifying elements r₀ arranged inversely in lines 34 and 35.

When the brush AR comes into contact with a 75 ramp C, a current flows through the main circuit

described above in a direction fixed by the sign of the polarization imposed by the local battery A and depending on the position of the switch B, this current being either pulsating or of constant value, according as the local alternating voltage source 8 is switched in or out by the switch R₁.

This current according to its direction, energizes one or other of the relays R_b and R_c.

The circuit in the one direction may be traced 10 from the positive pole of battery A, by lead 16, through the lower right-hand contacts 28, 27 of relay B, bridged by the blade 14, thence by arm 9 and contact 11 of switch R₁ through the secondary winding 3 of transformer T₁ (if switch 15 R₁ is in the raised position shown, but if not then direct by arm 9 and contact 12) to protecting resistance r, along the line 36 to ramp C, through brush AR in contact therewith, along the line 17 to arm 18 resting upon the lower (20) 20 of the top pair of contacts of relay R₀, by line 37, through the primary winding 29 of transformer T₂, by line 30, through the rectifier r₀ and connected winding of relay R_b and by line 31 to ground at M, thence through rails V, impedance r_b, along line 38, by the upper right hand contacts 26, 25, bridged by the blade 13 of relay B, by line 39 to the negative terminal of battery A. The corresponding circuit in the other direction, when the switch B occupies the opposite position, may be traced from the positive pole of battery A, which is grounded through the upper left-hand contacts 21, 22, now bridged by the blade 13 of relay B, along the line 38 to the impedance bond r_b and the running rails V, 35 and from ground at M by line 31 through the winding of relay R_c and its connected rectifier r₀, along line 39 to the primary winding 29 of transformer T₂, by line 37, through the lower (20) 40 of the top pair of contacts of relay R₀, by switch arm 18 and line 17 to brush AR and ramp C in contact therewith, along line 36, through protecting resistance r, by contact 12 or 11 to arm 9 of switch R₁ (direct or through the secondary winding 8 of transformer T₁ according as switch arm 9 is in lowered or in raised position), and through the lower left-hand contacts 23, 24 (now bridged by blade 14) of relay B, back by line 39 to the negative pole of battery A. Moreover, if the current is pulsating, 45 an induced alternating current which energizes the relay R_a, is impressed through the secondary winding 32 of the transformer T₂.

To the various values of the voltage mentioned above, impressed between the ramp C and the 55 running rails V, correspond respectively the following positions of the main relays R_a, R_b and R_c:

- (1) R_a energized, R_b energized, R_c de-energized.
- (2) R_a energized, R_b de-energized, R_c energized.
- (3) R_a de-energized, R_b energized, R_c de-energized.
- (4) R_a de-energized, R_b de-energized, R_c energized.

Each of these combinations is repeated or recorded by means of a circuit fed by a battery A₁ installed on the locomotive or vehicle, and closed by the operation of contacts controlled by the 65 armatures of the relays R_a, R_b and R_c, as indicated in Fig. 1. The relay R_a has an armature 60 directly connected to the positive pole of the battery A₁ and working between contacts 61, 62, which are respectively connected by lines 63, 64 70 and 65, 66 to the upper and lower armatures of the other relays R_b and R_c. The upper armature 67 of the relay R_b works between contacts 68 and 69, of which the upper one 68 is connected by a lead 70 to the first recording relay 1; the upper 75

armature 71 of the relay R_c works between contacts 72 and 73, of which the upper one 72 is connected by a lead 74 to the second recording relay 2; the lower armature 75 of the relay R_b works between contacts 76 and 77, of which the upper one 76 is connected by a lead 78 to the third recording relay 3; the lower armature 79 of the relay R_c works between contacts 80 and 81, of which the upper one 80 is connected by a lead 82 to the fourth recording relay 4. Normally all the armatures rest upon their lower contacts, of which only the contact 62 has an electrical connection onwards, but upon energization of one or more of the three relays, the armatures 15 60, 67, 71, 75 and/or 79 of the corresponding relays are attracted upwards to close a particular circuit determined by the combination. The circuit thus closed energizes the electromagnet α of one of the four recording relays, similar to the 20 relays used for telephone switchboard drops; the corresponding armature rises and disengages the movable shutter v brought into action by means of a spring d . The shutter v , once disengaged, closes an auxiliary circuit, which lights the corresponding 25 indicator or tell-tale lamp l indicating the nature of the indication received, and energizes an electromagnet α ; this auxiliary circuit may be traced from the positive pole of battery A_1 , along the lead 40, to the left hand ends 30 of the several electromagnets α , through the winding of one of these electromagnets (for example, the uppermost one, as determined by the particular shutter v released by the selected electromagnet α) and the corresponding lamp l , 35 through the contacts 41 closed by the released shutter v , from the latter by the connected lead 42 to the common return conductor 43 of the electromagnets α , and so back to the negative pole of battery A_1 . The particular electromagnet α energized according to the indication received actuates a recording pen (not shown in the drawings) corresponding to this indication and/or any other visible or audible signals, and, if desired, causes the brakes to be applied automatically upon receipt of the indication "line closed", or "second warning".

Condensers γ placed in parallel with the electromagnet windings α and an adjustable resistance ρ placed in series with the common return conductor 43 from these electromagnets, enable the release of the recording relays to be slightly delayed, so that they come into operation only after confirmation of the position of the three main relays R_a , R_b and R_c , which work almost instantaneously.

The recording of the signal indications received can besides be obtained by any other device serving the same purpose, for instance by relays with auxiliary holding contacts, as represented in Fig. 2.

The indication recorded when the train runs by a signal remains displayed until the train is about to reach the next signal.

At this moment, the second brush or front brush AV , carried by the locomotive or driver's vehicle and placed at a distance a little greater than the length of the ramp C in front of the brush AR mentioned above (the direction of train travel being indicated by the arrow placed between the rails V), makes contact with the ramp C and feeds the non-polarized relay R_o , which responds instantly to the direct current, pulsating or not, issued from the local signal device; the circuit for this relay may be traced from the battery A to the ramp C as given above for the

relays R_b and R_c , thence from ramp C by brush AV and line 44 to the winding of relay R_o , and by line 45 to join the line 31 connected to ground at M_1 and so back to the battery. The armature of this relay then lifts the armature 18 from the contact 20 against the dummy contact 19 and thereby interrupts the circuits of the main relays R_b and R_c , and in the case of Fig. 1 also lifts the lower armature 46 against the upper contact 47 of a second pair of contacts 47, 48, whereupon the locomotive battery A_1 feeds by line 49, contact 47, armature 46, and line 50 the circuits of electromagnets β which restore to their initial position the shutters v previously released by the electromagnets α . In the case of Fig. 2, the relay R_o lifts its lower armature 46 from the lower contact 51 of the second pair, and thereby breaks the circuit from the battery A_1 by lines 52, 53, feeding the common lead 54 of the holding circuits of the recording relays. The locomotive apparatus is then ready to receive and to record the new signal indication at the passage of the rear brush AR over the ramp C , as previously described.

Fig. 2 gives the detail of an arrangement slightly different from that of Fig. 1, and enables a fifth signal-indication to be recorded. This arrangement includes, in addition to the arrangement previously described, an additional switch I for the local apparatus. This switch is actuated by a relay from the signal cabin and able to take up two positions: the first position places in circuit the battery A of the local device by the engagement of the switch arm 55 with the contact 56 (as shown in Fig. 2), the other position with the arm 55 resting on a contact 57 connected by line 58 to the negative pole, puts this battery out of circuit. The fifth signal-indication will be given by setting the switch I in the second position, with the switch R_1 in the up position, that is with the arm 9 against the contact 11. Then, to the ramp C is applied the alternating voltage alone, which energizes simultaneously, on the locomotive device, the three relays R_a , R_b and R_c ; the relay R_a is energized by the two half-waves of the alternating current, R_b by the positive half-waves and R_c by the negative half-waves of the alternating current, which causes the circuit of the fifth recording relay to close.

It will be noted that in this arrangement the upper armature 67 of the relay R_b works between two contacts 68 and 69 which are both connected by leads 83 and 84 respectively to separate armatures 85 and 86 of the relay R_c , the latter having three armatures instead of two as in Fig. 1. The upper armature 85 of the relay R_c works between contacts 87 and 88 connected respectively by leads 89 and 90 to the fifth and first recording relays 5 and 1, while the middle armature 86 works between two contacts 91 and 92, of which the upper one 91 is connected by a lead 93 to the second recording relay 2. The lower armatures 75 and 79 of the relays R_b and R_c control contacts 76 and 80, connected to the third and fourth recording relays 3 and 4, as in the case of Fig. 1.

The windings of the relays R_b and R_c are, in this case, shunted by condensers γ' suitably adjusted to avoid vibration of the armatures, by preventing the coils from being completely de-energized during the half-waves not received by them.

It is naturally allowable to arrange the component parts in different ways so as to obtain

various arrangements working practically in the same manner as the examples described above with reference to Figs. 1 and 2.

What I claim is:—

5. 1. In a railroad signaling system, comprising track apparatus, vehicle apparatus, electrical connections established between said track apparatus and said vehicle apparatus at the passage of the vehicle, a source of direct current, a source 10 of alternating current of lower maximum voltage than said source of direct current, means for bringing said source of direct current into circuit with said electrical connections in either direction of polarity, and other means for bringing 15 said source of alternating current into circuit with said electrical connections, the combination in said electrical connections of two separate conducting members adapted to make contact successively with an individual conducting 20 member having relative motion to said separate conducting members at said passage, one of said two separate conducting members controlling the setting of said vehicle apparatus in condition for receipt of signaling current, and the 25 other of said two separate conducting members controlling the response of said vehicle apparatus upon receipt of subsequent signaling current.
2. In a railroad signaling system, comprising 30 track apparatus, vehicle apparatus, electrical connections established between said track apparatus and said vehicle apparatus at the passage of the vehicle, a source of direct current, a source of alternating current of lower maximum 35 voltage than said source of direct current, means for bringing said source of direct current into circuit with said electrical connections in either direction of polarity, and other means for bringing said source of alternating current into circuit 40 with said electrical connections, the combination of two separate conducting members on the vehicle, an individual conducting member on the track, all said conducting members being in-

cluded in said electrical connections, with part of said vehicle apparatus responsive only to the voltage obtained from said source of direct current in either direction of polarity, said part of said vehicle apparatus receiving current by one 5 of said separate conducting members, and other part of said vehicle apparatus responsive selectively to different voltage-combinations obtained from said sources of direct and alternating current, said other part of said vehicle apparatus 10 receiving current by the other of said separate conducting members.

3. In a railroad signaling system, comprising track apparatus, vehicle apparatus, electrical connections established between said track apparatus and said vehicle apparatus at the passage of the vehicle, a source of direct current, a source of alternating current of lower maximum voltage than said source of direct current, means for bringing said source of direct current into 15 circuit with said electrical connections in either direction of polarity, and other means for bringing said source of alternating current into circuit with said electrical connections, the combination of vehicle apparatus including main relays, responsive respectively to direct current in opposite directions of polarity and to alternating current, and an auxiliary relay responsive to direct current in either direction of polarity, the 20 operation of said auxiliary relay interrupting the 25 circuits of said main relays, and electrical connections including two separate conducting members on the vehicle and individual conducting members on the track, said auxiliary relay receiving current by the successive establishment 30 of connections with said individual conducting members by one of said separate conducting members, and said main relays receiving current by the successive establishment of connections with said individual conducting members 35 by the other of said separate conducting members.

ELISÉE AUGUSTE JOLY.
